ICE BUCKET

Louis J. Denton, 3218 Albright Court,
Indianapolis, Ind. 46268

Filed Jan. 26, 1973, Ser. No. 327,598

Term of patent 14 years

Int. Cl. D7—01

U.S. Cl. D7—78

Fig. 1

Fig. 2

Fig. 3

Fig. 4

FIG. 1 is a side elevation of an ice bucket showing my new design;

FIG. 2 is a front elevation thereof;

FIG. 3 is a rear elevation thereof; and

FIG. 4 is a perspective view thereof, but showing the lid in raised position.

I claim:

The ornamental design for an ice bucket, as shown and described.
